UNITED STATES PATENT OFFICE

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Desgn No. **6,855**, dated September 2, 1873; application filed August 9, 1873.
[Term of Patent 3½ years.]

d.

To all whom it may concern:

Be it known that I, FREDERICK WINK, of the city and county of Philadelphia, State of Pennsylvania, have invented a Design for Shawl-Pattern, of which the following is a specification:

The design, shown by the figure in the accompanying drawing, consists of a wide stripe, A, upon a plain ground, the said stripe being composed of a great number of minor parallel plain stripes of different widths and shades or colors, and being ornamented by a central rib, a, and rib b, about midway between the center and edge of the stripe, the said ribs a and

b being ornamented by alternate groups of dots and dashes, arranged in a manner so clearly shown in the drawing as no need no minute description.

Irrespective of the colors employed, I claim—

The design for a shawl-pattern, as described, and as represented in and by the accompanying drawing.

In testimony whereof I have signed my name to this specification in the presence of two subscribing witnesses.

Witnesses: FRED. WINK.
